UPPER HOUSING FOR AN ELECTRIC HAND MIXER

Richard B. Hall, Glen Ellyn, Ill., assignor to Sunbeam
Corporation, Chicago, Ill.

Filed June 24, 1971, Ser. No. 156,585

Term of patent 14 years

Int. Cl. D7—04

U.S. Cl. D44—1

FIG. 3.

FIG. 5.

FIG. 6.

FIG. 1 is a front side perspective view of an upper housing for an electric hand mixer showing my new design with broken lines to illustrate the lower housing and beaters which are included to show the environment only;

FIG. 2 is a left side elevational view thereof;

FIG. 3 is a top plan view thereof;

FIG. 4 is a front elevational view thereof;

FIG. 5 is a rear elevational view thereof; and

FIG. 6 is a sectional view taken along line 6-6 of FIG. 2.

I claim:

The ornamental design for an upper housing for an electric hand mixer, as shown and described.
